HOCKEY CONTEST STRUCTURE

Thomas M. Holleran, 16932 School St., South Holland,
Ill. 60473, and Frederick T. Green, 1804 Camellia,
Munster, Ind. 46321

Filed July 6, 1971, Ser. No. 160,251

Term of patent 14 years

Int. Cl. D21—03

U.S. Cl. D34—5 L

FIG. 1 is a perspective view of a hockey contest structure showing our new design;

FIG. 2 is an elevation view on an enlarged scale;

FIG. 3 is a plan view of FIG. 2, the pennants are omitted for convenience of illustration;

FIG. 4 is an elevation view on a reduced scale looking from the left; and

FIG. 5 is an elevation view on a reduced scale looking from the right.

We claim:

The ornamental design for a hockey contest structure, substantially as shown and described.
